CLOTH ROLL DRIVE

Horace H. Burdett, Milford, Mass., assignor to
 Draper Corporation, Hopedale, Mass., a corporation of Maine

Application May 13, 1940, Serial No. 334,803

6 Claims. (Cl. 139—304)

The present invention pertains to loom take-ups, and more particularly to the cloth roll drive thereof.

In loom take-ups of the type to which my invention applies, the cloth is wound onto a cloth roll which is driven from a rotating driving member by friction shoes engaging the driving member. The cloth roll has a gudgeon on which the driving member is loosely mounted. The friction shoes 5 have positive driving connection with the gudgeon and spring means urge the shoes into engagement with the driving member. Manual rotation of the cloth roll, for removing the cloth therefrom or for other purposes, cannot be conveniently accomplished unless the cloth roll is released or freed from the driving member.

Loom take-ups of the type above mentioned, as heretofore constructed commercially, were so arranged that the cloth roll could be freed from the driving member only by unscrewing adjusting nuts which were provided for adjusting the tension of the aforesaid spring means. The unscrewing of such adjusting nuts is a time consuming operation, and is further objectionable in that it destroys the 20 adjustment and thus provides an opportunity for improper readjustment of the tension on the friction shoes. Several attempts have been made to overcome this objectionable feature of the commercial form of cloth roll drive, but the constructions proposed heretofore have not been satisfactory for various reasons, which need not be discussed.

A principal object of the present invention is to provide, in a cloth roll drive for loom take-ups, 35 a cloth roll having a rotating driving member on the gudgeon, friction shoes connected to the gudgeon, spring means for urging the shoes into engagement with the driving member as aforesaid, novel manually operable cam means carried by the gudgeon and operable to adjust the pressure of the spring means, and locking means for holding the cam means in adjusted position.

A further object of the invention is the provision of adjustable stop means whereby after a 45 release of the driving member by the friction shoes, the shoes may again be moved into contact with the driving member under the same tension as before such release.

The foregoing and other objects of the invention are accomplished in the construction illustrated on the accompanying drawing, of which:

Fig. 1 is a perspective view of part of a loom having the preferred embodiment of my invention 55 applied thereto;

Fig. 2 is a detail view, to a larger scale of certain parts shown on Fig. 1;

Fig. 3 is a cross section view taken on line 3—3 of Fig. 2; and

Fig. 4 is a cross section view taken on line 4—4 of Fig. 3.

The drawing shows parts of a loom frame, including the front part of a right hand loom side 1, a breast beam 2, a girt 3 and a vertical stand 4 which is supported by the breast beam and girt. A 10 take-up roll or feed roll 5 is journaled in suitable bearings supported by stands such as the stand 4. The take-up roll 5 is positively revolved at a uniform speed, to feed the cloth forwardly in the loom, by any suitable usual means not shown. The 15 cloth C which is thus fed by the take-up roll is wound onto a roll 6 commonly called a cloth roll. The cloth roll must revolve at a comparatively faster rate when substantially empty than when nearly full, the rate progressively decreasing as 20 the diameter of the cloth supply increases.

The cloth roll 6 has a fixed shaft or gudgeon 7 projecting from the end thereof, which shaft or gudgeon may be journaled in a bearing 8 supported by the stand 4. The varying speed of the 25 cloth roll requires that the roll be driven by a friction or slipping drive and such drive is commonly effected from a rotating driving member loosely mounted on the cloth roll shaft or gudgeon. In the embodiment shown, the outer or driving 30 member 9 includes a friction drum 10 and a sprocket 11 formed integrally with the drum. A chain 12 passes around sprocket 11 and around a sprocket 13 which revolves with the take-up roll 5, whereby the member 9 is revolved by the take-up roll. The drum 10 includes a disc 13 having an 35 annular flange 14, against the inner surface of which the friction means carried by the inner or driving member 15 engages.

In the embodiment shown the inner or driven 40 member 15 is located within said outer or driving member 9 and is fixedly attached to the gudgeon 7. The driven member 15 includes a disc 16 having a curved slot 17 therein, for a purpose later to be disclosed, and an integral sleeve 18, the sleeve 45 18 being fixedly secured to gudgeon 7 by set screws 19. Two inwardly projecting, oppositely disposed studs 20 and 21 are carried by the disc 16. Pivoted on stud 20 is a friction shoe 22, also pivoted on stud 20 is a cam follower 23. Pivoted on stud 21 50 is a friction shoe 24, also pivoted on stud 21 is a cam follower 25. Friction shoes 22 and 24 are curved to fit the inner periphery of flange 14 and have a friction material such as leather 30 secured to their outer surface. The friction shoes 55

- 22 and 24 are adapted to be pressed outwardly into contact with the inner surface of the flange 14 on drum 10.
- In the embodiment shown, manually adjusted resilient means are provided for pressing the friction shoes outwardly into contact with the drum. Such means include a member 26 loosely mounted on gudgeon 7 and within drum 10. The member 26 has oppositely disposed cam surfaces 27 and 28.
- 10 The pivoted cam follower 23 rides on cam surface 28 and pivoted cam follower 25 rides on cam surface 27. Interposed between friction shoe 22 and cam follower 25 is a coiled compression spring 29 held in place by projection 31 on shoe 22 and projection 32 on cam follower 25. Interposed between friction shoe 24 and cam follower 23 is a coiled compression spring 33 held in place by projection 34 on shoe 24 and projection 35 on cam follower 23. The cam surfaces 27 and 28 are so constructed 20 and arranged that upon rotation of member 26 in one direction the cam followers 23 and 25 increasingly press against springs 29 and 33, and upon rotation in the opposite direction pressure on the springs is reduced.
- 25 Cam surface 27 and cam follower 25 have cooperating serrations 36 and 37 respectively to provide a step by step adjustment of the pressure exerted on the springs and also hold or lock the member 26 in the selected adjusted position.
- 30 The member 26 has a manually operable lever 38 fixedly secured thereto, the lever 38 is offset from member 26 so that the lever 38 may extend through the curved slot 17 in disc 16, and thereby provide an external handle 39. A pair of stops 35 40 and 41 are provided adjacent the periphery of disc 16 to limit the movement of handle 39. Stop 40 comprises a fixed projection integral with disc 16. Stop 41 is adjustable and comprises a member 42 curved to conform with the outer periphery of disc 16 and provided with a slot 43. A plurality of spaced holes 44 are provided adjacent the peripheral edge of disc 16. Member 42 may be adjustably secured to disc 16 by means of a bolt 45 passing through slot 43 in member 42 and engaging in either of holes 44. This gives a broad adjustment of stop 41. The slot and bolt connection of member 42 to disc 16 provides for a minute adjustment of stop 41. The operation of the device is as follows:
- 50 With the handle 39 resting upon fixed stop 40 substantially no pressure is exerted on springs 29 and 33 and accordingly the outward pressure on friction shoes 22 and 24 is very slight and driving member 9 and driven member 15 are free 55 to move relative to each other. In this position when the loom is stopped and member 9 is stationary, the cloth roll may be freely rotated manually by any means such as hand wheel 46 which is fixedly secured to gudgeon 7. Upon the movement of handle 39 toward stop 41, member 26 is rotated, cam followers 23 and 25 ride up the cam surfaces 28 and 27 and springs 29 and 30 are brought under increasing tension thereby causing friction shoes 22 and 24 to be pressed 60 outward into contact with the inner surface of flange 14 and driven member 15 is frictionally engaged with driving member 9 whereby upon rotation of driving member 9, driven member 15 will be rotated and through member 15 the cloth 65 roll 6. It should be noted that the cooperating serrations on the cam surface 27 and cam follower 25 provide a step by step adjustment of the outward pressure to be exerted upon the friction shoes 22 and 24 and also serves as means for 70 locking the device to such adjusted pressure.

The adjustable stop 41 may be set to a predetermined adjusted position whereby upon handle 39 being brought up against stop 41 the member 26 is rotated to an extent to exert through the cam follower and springs a predetermined pressure on the friction shoes, thereafter upon each movement of handle 39 into abutment with stop 41 the same predetermined adjusted pressure will be exerted upon the friction shoes.

5 While the outer member 9 has been described 10 as the driving member and the inner member 15 has been described as the driven member, it should be noted that it is immaterial which member is the driving or driven member. By providing member 15 with a sprocket and loosely 15 mounting it on gudgeon 7 and fixedly mounting member 9 on gudgeon 7, member 15 becomes the driving member and member 9 the driven member.

Having fully disclosed the preferred embodiment of my invention, I claim:

1. In a take-up mechanism of a loom, the combination with the cloth roll shaft of a friction clutch attached thereto, said clutch comprising an outer member and an inner member mounted 25 on said shaft, one of said members being fixedly connected to said shaft to rotate therewith, the other of said members being freely rotatable on said shaft, friction means pivotally connected to said inner member and adapted to be moved outwardly into contact with said outer member, resilient means for pressing said friction means outwardly, means for adjusting the pressure of said resilient means, and means for driving said freely rotatable member from a moving part of 30 the loom.

2. In a take-up mechanism of a loom, the combination with the cloth roll shaft, of a friction clutch attached thereto, said clutch comprising an outer member and an inner member mounted on said shaft, one of said members being fixedly connected to said shaft to rotate therewith, the other of said members being freely rotatable on said shaft, friction means pivotally connected to said inner member and adapted to be pressed outwardly into contact with said outer member, resilient means for pressing said friction means outwardly, cam means for adjusting the pressure of said resilient means, and means for driving said freely rotatable member from a moving part of 50 the loom.

3. In a manually releasable cloth roll drive for loom take-ups, the combination of a cloth roll shaft, an outer member, and an inner member one of said members being loosely mounted on said shaft, the other of said members being fixedly mounted on said shaft, said outer member comprising a revolving friction drum, said inner member comprising a disc rotatable within said drum, a pair of friction shoes pivoted to said disc and curved to fit the inner periphery of said drum, resilient means adapted to press said shoes outwardly into contact with said drum, cam means for adjusting the pressure of said resilient means, means for locking said cam means in adjusted position, and means for driving said loosely mounted member from a moving part of the loom.

4. In a take-up mechanism of a loom, the combination with the cloth roll shaft, of a friction clutch attached thereto, said clutch comprising an outer member and an inner member, one of said members being freely rotatable on said shaft, the other of said members being fixedly connected to said shaft to rotate therewith, friction shoes pivotally connected to said inner member and 70
